UNITED STATES PATENT OFFICE

127,632

DESIGN FOR A DRESS ENSEMBLE

Mary Geller, Chicago, Ill.

Application December 28, 1940, Serial No. 97,669

Term of patent 3½ years

To all whom it may concern:

Be it known that I, Mary Geller, a citizen of Union of the Soviet Socialist Republics, residing at 1350 Estes Avenue, Chicago, in the county of Cook and State of Illinois, have invented a new, original, and ornamental Design for a Dress Ensemble, of which the following is a specification, reference being had to the accompanying drawings, forming part thereof.

I claim:

The ornamental design for a dress ensemble, substantially as shown.

MARY GELLER.
